Madison Shipman Inventor

UNITED STATES PATENT OFFICE.

MADISON D. SHIPMAN, OF DE KALB, ILLINOIS.

DESIGN FOR A BUTTON.

SPECIFICATION forming part of Design No. 32,721, dated May 29, 1900.

Application filed May 1, 1900. Serial No. 15,136. Term of patent 14 years.

To all whom it may concern:

Be it known that I, MADISON D. SHIPMAN, a citizen of the United States, residing at De Kalb, in the county of De Kalb and State of Illinois, have invented and produced a new and original Design for Buttons; and I do declare the following to be a full, clear, and exact description of the same, reference being had to the accompanying drawings, forming 10 a part thereof.

My present invention relates to new and original designs for buttons.

In the accompanying drawings, which form a part of this specification, Figure 1 is a plan 15 view of a button, showing my new and original design. Fig. 2 is an edge view thereof.

Referring to the drawings, and more especially to Fig. 1, it will be seen that the central portion of the button has formed thereon a

spiral figure comprising a series of fine lines 20 starting at a common center and gradually enlarging the figure as they extend spirally outward to their place of termination. A series of slightly-curved rays extend outward from the outer edge of the spiral figure to- 25 ward the perimeter of the button.

The distinctive feature of this design consists in the central spiral figure and the encircling curved rays.

Having thus fully described my invention, 30 what I claim is—

The design for a button, substantially as shown and described.

MADISON D. SHIPMAN.
